CRYSTAL RECTIFIER CONVERTER

John B. Atwood and Bertram Trevor, Riverhead,
N. Y., assignors to Radio Corporation of Amer-
ica, a corporation of Delaware

Application December 1, 1943, Serial No. 512,442

10 Claims. (Cl. 250—20)

1

The present invention relates to converters, and more particularly to converters for ultra-high frequency super-heterodyne receivers.

An object of the present invention is the provision of a converter circuit for an ultra-high frequency super-heterodyne receiver.

Another object of the present invention is the improvement of crystal rectifier converter circuits.

Another object of the present invention is the provision of a balanced converter circuit for ultra-high frequency super-heterodyne receivers.

A further object of the present invention is the provision of a balanced converter arrangement having a low degree of coupling between the oscillator and signal circuits.

A further object of the present invention is the reduction of oscillator radiation into the antenna circuit of a super-heterodyne receiver.

Still a further object of the present invention is to prevent the loss of incoming signal energy in the oscillator circuit of a super-heterodyne receiver.

The foregoing objects and others which may appear from the following detailed description are obtained in accordance with the principles of the present invention by the provision of a crystal rectifier converter arranged in the form of a balanced circuit whereby little, if any, of the applied oscillator voltage is transferred to the antenna circuit. The conversion or mixing action in the circuit is performed by a pair of crystal rectifiers arranged in a push-pull relationship. Preferably all of the resonant circuit elements in the converter circuit are constituted by line sections having uniformly distributed constants. Means are provided for entirely shielding the converter circuit, and further means are provided for matching the impedance of the signal input circuit to the impedance of the transmission line connected thereto.

The invention will be more fully understood by reference to the following detailed description, which is accompanied by a drawing in which:

Figure 1 is an electrically equivalent circuit of the present invention which utilizes lumped circuit constants, and which is useful in understanding the operation of the invention; while

Figure 2 illustrates in detailed cross-section an embodiment of the invention.

In Figure 1, there is illustrated a tuned circuit 1 including an inductance 2 and a tuning capacity 3. Across the ends of the tuned circuit 1 are connected a pair of crystal rectifiers 4 and 5 arranged in a push-pull relationship. Oscilla-

2

tory wave energy from any desired source such as a local oscillator is coupled into tuned circuit 1 by a coupling link 6. Incoming signal energy such as from antenna 7 is applied to the system across a variably tapped inductance 8 connected between a center tap on coil 2 and a point of zero reference potential such as that indicated by the ground symbol.

The best frequency resulting from the mixture of the oscillatory wave energy applied to the circuit through coupling link 6 and the incoming signal energy from antenna 7 is abstracted from the circuit through the medium of an output circuit 9 which is connected to the following intermediate frequency amplifier (not shown).

It will be noted that the coupling inductance 8 for the antenna circuit is mounted in the system at a point of substantially zero potential with respect to ground for energy from the oscillator circuit. Therefore, none of this energy is supplied to the antenna 7. Similarly, substantially none of the signal energy from antenna 7 is coupled into the oscillator link 6 due to the opposing phase relationships of the signal current through inductance 2.

The actual mechanical construction of the converter of the present invention is shown in detail in Figure 2, wherein the tuned circuit 1 of Figure 1 is constituted by a resonant line structure 10. The resonant line structure includes a pair of parallel conductors 11 and 12 insulatingly supported within an outer casing 13 by insulators 17. The insulating supports are preferably of some low loss material such as polystyrene or methyl-methacrylate. A conductive wall 14, electrically a part of casing 13, is mounted between rods 11 and 12 so that each of the rods 11 and 12, together with the surrounding conductive wall structure, constitutes a coaxial line section. Rods 11 and 12 are connected together at each end with adjustable shorting bars 15, 15. These bars may be slid along the length of rods 11 and 12 to such position that the total included length between the shorting bars is of the order of three quarters of the operating wavelength. Clamping screws 16 are provided at each end of the shorting bars 15, 15 to rigidly clamp the shorting bars in position.

The oscillator input is coupled to the tuned circuit 10 by means of a coaxial line fitting 18 including an outer threaded shell 19 connected to casing 13, and an inner conductor 20 coupled to rod 12 of the resonant circuit 10. Conductor 20 is maintained in coaxial alignment with threaded sleeve 19 by means of insulating washers 21. The

point of connection of conductor 20 to rod 12 is preferably spaced a distance equal to one quarter of the operating wavelength from one end of shorting bar 15.

The signal input to the converter from an antenna (not shown) is applied to coaxial line fitting 22 which is similarly constructed to fitting 18. The inner conductor 20 of coaxial line fitting 22 carries on its inner end a spring 23 bearing against stub 24 of a quarter wave resonant circuit 25. The signal input coaxial fitting 22 is mounted on a plate 26 so arranged that the entire fitting may be slid up and down, thus changing the effective size of the coupling loop constituted by inner conductor 20, spring 23 and stub 24.

Tuning of the quarter wave resonant circuit 25 may be accomplished by providing a rod 30 arranged for slidable operation within stub 24. Preferably the rod 30 is so arranged, as by a slot and key construction 31, that it will only slide and not turn within stub 24. Rod 30 is hollow and threaded on its inside for threaded engagement with rod 32. Thus, as rod 32 is rotated by means of knurled knob 33, the effective length of rod 30 protruding from stub 24 may be adjusted to the desired quarter wave relationship.

The resonant line structure 10 is coupled to the quarter wave resonant circuit 25 by means of a wire 34 connected to shorting bar 15 and to stub 24 at a predetermined point. Wire 34 passes through an aperture in the end wall of the casing 13 surrounding the resonant line structure 10, and is maintained in insulated relationship thereto by an insulating button 35.

The quarter wavelength circuit 25 between the antenna input 22 and the converter acts as an impedance matching device, the antenna match being adjustable to accommodate various antennas, etc. The connection 34 from circuit 25 to the tuned line 10 is fixed at a predetermined point on stub 24 since the impedance of the line sections is substantially constant over a reasonable operating range of frequencies.

The crystal rectifiers 40 and 41 are arranged to plug in at one end to spring clips 42 and 43 carried by rods 11 and 12. Electrical contact to the other end at each of the rectifiers 40 and 41 is provided by springs 45 carried by a conductive plate 46. Conductive plate 46 is insulated from the conductive body of casing 13 by means of a thin strip of insulation 47 which may be of mica, and by means of insulating washers 47' under the heads of the securing screws. Thus, a by-pass condenser for signal frequencies is provided between the effective cathode of each of the crystal rectifiers and the grounded casing 13. This by-pass capacity is, however, too small to substantially attenuate the intermediate frequency output of the converter which is conducted by means of coaxial lines 48 and 49 to the desired intermediate frequency coupling circuits.

In order to entirely shield the rectifiers 40 and 41 from outside influences, shielding caps 50 and 51 are provided. These are designed to thread onto threaded mounts 52 and 53 carried on the casing 13. In order to insure that the crystal rectifiers 40 and 41 are maintained in position in spite of vibration and so forth, springs 54 are centrally mounted within caps 50 and 51 and arranged to bear on the outer ends of crystal rectifiers 40 and 41. In order to prevent shorting of the intermediate frequency output, springs 54 are insulated from caps 50 and 51 by means of interposed insulating blocks 55 and 56.

It will be noted that the distance from the oscillator input tapping point 20 to crystal tap 43 is $\lambda/4$, where λ is the operating wavelength. The distance from 20 to 42 is $3\lambda/4$. Therefore, these points are $3\lambda/4 - \lambda/4 = \lambda/2$, or 180° apart, and hence are in push-pull relationship. That 34 is a center tap necessarily follows from the arrangement such that distances 34-42, 34-43 are each $\lambda/4$.

Since at the contemplated operating frequencies the difference between the oscillator and signal frequencies is so slight as to be a second order effect, either frequency may be used in calculating the line lengths to be used.

While we have illustrated a particular embodiment of the present invention, it should be clearly understood that it is not limited thereto since many modifications may be made in the several elements employed and in their arrangement, and it is therefore contemplated by the appended claims to cover any such modifications as fall within the spirit and scope of the invention.

Having now described our invention, what we claim as new and desire to have protected by Letters Patent is:

1. A converter circuit including a pair of parallel coaxial line sections each including an inner conductor and a surrounding outer shell, said inner conductors being connected together at each end, means for applying wave energy of one frequency across said line sections in a parallel relationship, means for applying wave energy of another frequency to said line sections in a push-pull relationship, and a pair of rectifier elements connected in a symmetrical arrangement from opposing points on said inner conductors to an output circuit.

2. A converter circuit including a pair of parallel coaxial line sections each including an inner conductor and a surrounding outer shell, said inner conductors being connected together at each end, means for applying wave energy of one frequency across said line sections in a parallel relationship, means for applying wave energy of another frequency to said line sections in a push-pull relationship, a pair of crystal detectors each having a terminal connected in a symmetrical arrangement to opposing points on said inner conductors, bypass condensers connected from each of the other terminals of said crystal detectors to a point of zero reference potential, and an output circuit connected across said other terminals.

3. A converter circuit including a pair of parallel coaxial line sections each including an inner conductor and a surrounding outer shell, said inner conductors being connected together at each end, means for applying wave energy of one frequency across said line sections at one end in a parallel relationship, means for applying wave energy of another frequency to said line sections in a push-pull relationship, and a pair of rectifier elements connected in a symmetrical arrangement from intermediate high potential points on said inner conductors to a balanced output circuit.

4. A converter circuit including a pair of parallel coaxial line sections each including an inner conductor and a surrounding outer shell, said inner conductors being connected together at each end, each of said conductors having a length equal to three quarters of the operating wavelength, means for applying wave energy of one frequency across said line sections at one end in a parallel relationship, means for applying wave energy of another frequency to one of

said line sections at a distance of one quarter wavelength from the other end whereby said conductors are energized in a push-pull relationship, and a pair of crystal detectors each having a terminal connected in a symmetrical arrangement to one of said inner conductors at a distance of one quarter wave length from said one end, other terminals of said detectors being connected to an output circuit.

5. A converter circuit including a pair of parallel coaxial line sections each including an inner conductor and a surrounding outer shell, said inner conductors being connected together at each end, means for applying wave energy of one frequency across said line sections at one end in a parallel relationship, said means including an impedance matching network connected between the source of said wave energy and said line sections, means for applying wave energy of another frequency to said line sections in a push-pull relationship, and a pair of rectifier elements connected in a symmetrical arrangement from intermediate high potential points on said inner conductors to a balanced output circuit.

6. A converter circuit including an elongated conductive housing having a longitudinal partition therein, an inner conductor in each chamber of said housing, said inner conductors being connected together at each end, means for applying wave energy of one frequency between said inner conductors and said housing at one end in a parallel relationship, said means including an impedance matching network connected between the source of said wave energy and said conductors, means for applying wave energy of another frequency to one of said conductors at such distance from one end that said conductors are energized in a push-pull relationship, and a pair of rectifier elements connected in a symmetrical arrangement from intermediate high potential points on said inner conductors to a balanced output circuit.

7. A converter circuit including an elongated conductive housing having a longitudinal partition therein, an inner conductor in each chamber of said housing, said inner conductors being connected together at each end, means for applying wave energy of one frequency between said inner conductors and said housing at one end in a parallel relationship, said means including an impedance matching network connected between the source of said wave energy and said conductors, means for applying wave energy of another frequency to one of said conductors at such distance from one end that said conductors are energized in a push-pull relationship, a pair of detectors extending through the wall of said housing each having a terminal connected to one of said inner conductors at a distance of one quarter of the operating wave length from said one end, connections from the outer ends of each of said detectors to an output circuit, and conductive shield caps over each of said outer ends.

8. A converter circuit including an elongated conductive housing having a longitudinal partition therein, an inner conductor in each chamber of said housing, said inner conductors being connected at each end, means for applying wave energy of one frequency between said inner conductors and said housing at one end in a parallel relationship, said means including an impedance matching network including a quarter wave resonant line section having an outer shell and a variable length inner conductor, a connection from a fixed point on said inner conductor to

one end of the inner conductors, a connection from the source of said wave energy to an adjustable point on said variable length inner conductor, means for applying wave energy of another frequency to one of said conductors at such distance from one end that said conductors are energized in a push-pull relationship, a pair of detectors extending through the wall of said housing each having a terminal connected to one of said inner conductors at a distance of one quarter of the operating wave length from said one end, connections from the outer ends of each of said detectors to an output circuit and conductive shield caps over each of said outer ends.

- 5 9. A converter circuit including a pair of parallel coaxial line sections each including an inner conductor and a surrounding outer shell, said inner conductors being connected together at each end, means for applying wave energy of one frequency across said line sections at one end in a parallel relationship, said means including an impedance matching network including a quarter wave resonant line section having an outer shell and a variable length inner conductor, a connection from a fixed point on said inner conductor to one end of the inner conductors of said pair of line sections, a connection from the source of said wave energy to an adjustable point on said inner conductor, means for so applying wave energy of another frequency to an intermediate point on said line sections that said energy appears on said line sections in an opposing phase relationship, a pair of rectifier elements connected in a symmetrical arrangement from intermediate high potential points on said inner conductors to a balanced output circuit, said output circuit being so bypassed as to be responsive only to frequencies no greater than the difference between the frequencies of said applied wave energies.
- 10 10. A converter circuit including a pair of parallel conductors connected together at each end and an outer casing enclosing said conductors, a conductive wall between said conductors and connected to said outer casing, means for applying wave energy of one frequency between said line conductors and said outer casing, means for applying wave energy of another frequency to said line conductors in a push-pull relationship and rectifying means connected in symmetrical relationship from corresponding high potential points on said conductors to an output circuit.
